COMBINED CLOTHES AND CARPET BRUSH

Samuel J. Popeil and Raymond Popeil, Chicago, Ill.,
assignors to Popeil Brothers, Inc., Chicago, Ill.

Filed Dec. 15, 1969, Ser. No. 20,519

Term of patent 14 years

Int. Cl. D28—03; D4—01
U.S. Cl. D86—13

FIG. 1

FIG. 2

FIG. 3

FIG. 4

FIG. 5

FIG. 6

FIG. 1 is a perspective view of the subject brush shown with the oriented fabric in the "top" position.

FIG. 2 is a perspective view taken from the same vantage point as FIG. 1 with the brush inverted showing the rotary brush portion in the "up" position.

FIG. 3 is a top view of the brush from the position shown in FIG. 1.

FIG. 4 is a front elevation of the brush as shown in FIG. 3.

FIG. 5 is a bottom view of the brush shown in FIGS. 3 and 4.

FIG. 6 is an end view (taken from either end) of the brush as shown in FIG. 4.

We claim:

The ornamental design for a combined clothes and carpet brush, as shown and described.
